SELF-THAWING RADIATOR

Luther Demaree Boyd, Louisville, Ky.

Application May 24, 1940, Serial No. 336,970

2 Claims. (Cl. 123—178.5)

This invention relates to radiators for internal combustion engines, one of the objects being to provide a radiator with means whereby the radiator cannot only be prevented from freezing while the motor is running but can also be thawed out after it has frozen, simply by operating the motor.

Various devices for preventing freezing of radiators and for thawing out radiators after they have been frozen, have been devised but, as far as I am aware, these have all been objectionable for one reason or another.

An object of the present invention is to provide a radiator with efficient means whereby the desired results can be obtained, this means operating to utilize not only steam for the purpose of raising the temperature in the radiator but also utilizing condensed steam for that purpose so that maximum efficiency is obtained.

A further object is to provide a means by which the condensed steam can be drawn off when it reaches a predetermined level so that it will not remain in the radiator too long and retard the thawing operation.

A still further object is to provide the radiator with a means for trapping the steam so that anti-freezing preparations contained within the radiator can be trapped and recovered.

Another object is to provide heating means which insures free flow of steam generated in the radiator so that it will not be unduly retarded while used for heating purposes.

A still further object is to provide the radiator with means for conducting steam along predetermined paths for the purpose of thawing a radiator if frozen and also for the purpose of delivering generated steam and excess water in warm weather when the thawing action is not desired.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a vertical transverse section through a radiator, the present improvements being shown positioned in the radiator.

Figure 2 is a perspective view of the upper

intake end of the device constituting the present invention, a portion being broken away.

Referring to the figures by characters of reference, R designates a radiator of the usual type used in connection with internal combustion engines in motor vehicles, this being provided with the usual filling opening 0. The radiator is to be provided with the usual water tubes shown at T.

10 The present invention includes a steam intake element 1 adapted to be positioned within the radiator close to the opening 0 and extending downwardly from this element are several tubes 2 so shaped as to extend downwardly between some of the water tubes T in the radiator and their lower ends are then extended to a condensing chamber 4 in the form of a box located in the lower portion of the radiator. This condensing chamber has an overflow pipe 5 extending upwardly from the top thereof and thence downwardly below the bottom of the radiator. A drain-cock 6 is also in communication with the bottom of the condensing chamber 4, this cock being normally closed during the thawing operation hereinafter described.

20 As shown particularly in Figure 2 the steam intake element 1 includes a tubular body portion 7 into which the upper ends of the tubes 2 extend, the transverse area of this body portion 7 being greater than the combined transverse areas of the tubes. The upper end of the tubular body portion 7 is provided with a dome-like cap 8 which extends radially beyond the body portion 7 to provide a shoulder 9 in which is located an annular series of steam inlet ports 10 the capacity of which is equal to or greater than the capacity of the body 7 and the tubes 2.

30 As before stated the present device is arranged within the radiator with the intake member 1 located close to the opening 0 while the condensing chamber 4 is located in the bottom portion of the radiator, the tubes 2 constituting steam conductors leading from the member 1 to the chamber 4.

40 Under warm weather driving conditions any steam generated within the radiator will pass through the ports 10 into the body 7 and thence downwardly through the tubes 2 to the chamber 4. The drain-cock 6 is open under these conditions and the steam therefore can flow outwardly through the drain-cock and also through the pipe 5 so that it will quickly leave the radiator and allow the water to cool.

50 Should the radiator be used in freezing weather the drain-cock 6 is closed. Thus steam generated

in the radiator will flow into the intake member 1 as before explained and thence downwardly through the tubes 2 to the condensing chamber 4, which is, in effect, an expansion chamber. This steam can only escape through the small overflow pipe 5, however, and therefore will be retarded within the tubes 2 and the chamber 4 so that it will be maintained at maximum efficiency as a heating medium for the ice in the radiator. Ultimately the steam will condense within the chamber 4 and should the water of condensation become excessive in amount, the drain-cock 6 could be opened to permit drainage.

The present invention takes the place of the usual overflow tube which obviously can be dispensed with when the improvements are installed in a radiator. Any excess water directed into the radiator will overflow through the member 1 and the tubes 2 and thence from the chamber 4 through the drain-cock 6, if opened, or else through the overflow pipe 5.

It has been found in practice that this invention is very efficient as a means for preventing a radiator from freezing while the motor is operating and also as a means for melting ice in radiators which have already frozen. It is furthermore advantageous because the water of condensation trapped within the chamber 4 during the thawing operation, will contain a portion of any anti-freezing preparation which might be within the radiator and by draining off the contents of this chamber, the anti-freezing mixture can be preserved and reused.

As the capacity of the body 7 is greater than that of the tubes 2 and as the ports 10 are proportioned to allow steam to flow freely into the body portion 7 it will be apparent that the steam will flow freely through these parts from the interior of the radiator when the drain-cock is open but, when the drain-cock 6 is closed, the steam will flow into the tubes 2 faster than it can escape through the small outlet pipe 5 with the result that the steam will be retarded in the pipes and in the chamber 4 and thus become more efficient as a thawing medium than would be the case should it flow through these parts freely or without restraint.

While the tubes 2 can be extended between certain of the tubes ordinarily found in the radiator it is to be understood that if preferred, the tubes 2 could in themselves be selected tubes of the radiator which are joined at their upper ends to the member 1 and at their lower ends to the chamber 4.

To insure proper operation of the invention it is desirable, especially in cold weather, to keep water out of the pipes 2 in order that steam and vapor may flow freely through the pipes to the

chamber 4. The hood 8 and tubular member 1 serve to protect the upper ends from water being poured into the radiator and from water splashing or otherwise in a state of agitation in the top portion of the radiator. In cold weather, when the drain cock 6 is closed, only a small outlet is provided by pipe 5 and water entering tubes 2 in large quantities would become partially trapped and might freeze with the other water in tubes 2 and in the top and bottom portions of the radiator. For efficient results under all conditions tubes 2 must be shielded. The small overflow pipe 5 allows air in chamber 4, tubes 2 and dome 8 to form in effect a cushion for resisting upflow of water through apertures 9 in shoulder 10. It will be noted that chamber 4 is set in from the walls so that water to be heated can circulate over and around the chamber and be tempered by the steam-warmed walls of the chamber.

What is claimed is:

1. The combination with a radiator having upper and lower water chambers and tubes connecting the chambers, of means for distributing heat throughout all portions of the interior of the radiator, said means including a container for water of condensation housed within the lower chamber and constituting an expansion chamber, and steam-conducting tubes positioned at their upper ends within the upper chamber and extended downwardly through the connecting tubes, said steam-conducting tubes opening at their lower ends into the top of the container, said steam-conducting tubes and the container constituting means for transmitting to the contents of the chambers and their connecting tubes the heat of the steam and of the water of condensation.

2. The combination with a radiator having upper and lower water chambers and tubes connecting the chambers, of means for distributing heat throughout all portions of the interior of the radiator, said means including a container for water of condensation housed within the lower chamber and constituting an expansion chamber, and steam-conducting tubes positioned at their upper ends within the upper chamber and extended downwardly through the connecting tubes, said steam-conducting tubes opening at their lower ends into the top of the container, said steam-conducting tubes and the container constituting means for transmitting to the contents of the chambers and their connecting tubes the heat of the steam and of the water of condensation, and an overflow pipe extending from the upper portion of the container and opening downwardly through the bottom of the radiator.

LUTHER DEMAREE BOYD.
